UNITED STATES PATENT OFFICE.

IRVING HORTON, OF EAST BRIDGEWATER, MASSACHUSETTS, ASSIGNOR OF SIXTY ONE-HUNDREDTHS TO JOHN C. SCHELTER, OF ROCHESTER, NEW YORK.

SHOE.

1,115,467.

Specification of Letters Patent.

Patented Oct. 27, 1914.

Application filed April 9, 1913. Serial No. 759,870.

To all whom it may concern:

Be it known that I, IRVING HORTON, a citizen of the United States, and resident of East Bridgewater, in the county of 5 Plymouth and Commonwealth of Massachusetts, have invented certain new and useful Improvements in Shoes, of which the following is a specification.

In the manufacture of certain kinds of 10 shoes the welt is sewed to the upper usually to a point extending back to about the front of the heel and the sole is then sewed to the welt. It happens that in certain grades of shoes continual bending of the shoe at 15 the shank causes a breakage of the threads and a separation of the sole from the welt at the point of bending.

To prevent this separation and consequent disfigurement of the shoe is the object of the present invention.

In the drawings herewith accompanying and making a part of this application, Figure 1 is a perspective view of a shoe showing my improved fastener secured thereto, 25 and Fig. 2 is an enlarged perspective view of the fastening device.

Same reference characters indicate like parts in the several figures.

In said drawing, A represents a shoe, B 30 the sole, C the welt, and D the line of separation between the sole and welt.

My improved fastening device consists of a thin narrow strip of material bent to corrugated form, preferably angular, although not necessarily so. This strip of metal E, preferably flexible, is inserted edgewise by pressure into the material forming the welt and sole, the corrugations extending transversely across the line between the 40 welt and sole, the apexes F on one side taking into the material forming the welt and the apexes G on the other side taking into the material forming the sole substantially as shown in Fig. 1. The fastener is forced 45 into position in the shoe edgewise after the shoe is completed, and being on the inside

where the separation invariably occurs is practically concealed from view. Some of the apexes, as A, may be provided with barbs H which project outwardly at an acute angle to the edge of the fastener. 50 These barbs offer little resistance to the insertion of the fastener but prevent it from accidentally working out. It will be understood that the edge I of the fastener 55 when provided with barbs is inserted first.

Having thus described my invention and its use, I claim:

1. The combination with a shoe having the bottom formed of a plurality of flexible 60 parts, of a fastener consisting of a thin narrow strip of corrugated material inserted edgewise in the edge of the shoe along the line of separation between two parts, the corrugations extending transversely across the line of separation to lock the parts together.

2. The combination with a shoe having the bottom formed of a plurality of parts at the shank, of a fastener consisting of a 70 thin narrow strip of corrugated material inserted edgewise in the edge of the shoe along the line of separation between two parts, the corrugations extending transversely across the line of separation to lock 75 the parts together.

3. The combination with a shoe having the bottom formed of a plurality of parts at the shank, of a fastener consisting of a thin narrow strip of corrugated material 80 inserted edgewise in the edge of the shoe along the line of separation between two parts, the corrugations extending transversely across the line of separation to lock the parts together, the fastener being 85 provided with barbs formed thereon to prevent the fastener from accidentally working out of place.

IRVING HORTON.
